UNITED STATES PATENT OFFICE.

ALEXANDRE GOURJU, OF LYON, FRANCE, ASSIGNOR TO ALFRED LECOMTE, OF LYON, FRANCE.

SOCKET FOR INCANDESCENT-ELECTRIC-LAMP HOLDERS.

1,302,787.

Specification of Letters Patent.

Patented May 6, 1919.

Application filed October 23, 1918. Serial No. 259,412.

To all whom it may concern:

Be it known that I, ALEXANDRE GOURJU, mechanic, of Lyon, France, a citizen of the French Republic, have invented certain new 5 and useful Improvements in Sockets for Incandescent-Electric-Lamp Holders, of which the following is a specification.

This invention has for its object a socket with circuit-breaker for incandescent electric lamp holders, the characteristic feature 10 of which is that it has no screwed, riveted or pinned member, nor any screw, nut, rivet or washer. All the metal parts comprised in it can be cut without any loss or waste from 15 sheet metal, thus dispensing with any turning, trimming, sawing, boring, screw-cutting, worming or molding work.

It is easily understood that such method of manufacture is eminently economical and 20 allows of production at considerably lower prices than that of similar holders which now exist.

A form of construction of the invention is 25 illustrated by the accompanying drawing in which

Figures 1 to 9 are detail views of the various parts which compose the socket.

Fig. 10 is a vertical section of the socket mounted in the lamp holder.

30 The socket comprises:—

1. A truncated cone-shaped member α of porcelain or any other insulating material. This member is shown in front view by Fig. 1 and Figs. 2 and 3 are sections taken on the 35 lines 2—2 and 3—3 respectively of Fig. 1. The member α is provided with a transverse hole b . In planes perpendicular to this hole it has a longitudinal groove c which extends from the top of the member to a cavity d 40 which crosses the hole b ; below this hollow is a small recess e situated in the extension of the groove c ; on the opposite side of the member α is a groove f reaching from the cavity d to the bottom of the member α and 45 communicating by a groove g with a circular bore h .

Parallel with the groove c or on the opposite side, is another groove i extending from the top to the bottom of the member α 50 and communicating by means of a small groove j with a circular bore k similar to h and arranged beside the latter.

Finally, at the upper part of the member α are two transverse openings l and m ,

the former communicating with the groove c 55 and the latter with the groove i .

2. A push-pin m (Fig. 4) of ebony or other suitable insulating material, which carries at a suitable point a metal ring n formed by a rolled up strip (Fig. 5). This 60 push-pin is mounted in the hole b of the member α (see Fig. 10).

3. A strip o bent into the shape shown in Fig. 6. The part o^1 engages in the opening l of the member α and serves to maintain 65 one of the line wires p (see Fig. 10) the part o^2 is placed in the groove c^1 and the curved part o^3 encircles the upper part of the push-pin m .

4. A strip q (Fig. 7) of which the part q^1 70 incloses the lower part of the push-pin and is bent over at q^2 in order to fit into the recess e , while the part q^3 lies in the grooves f and g and is formed at q^4 into a split cylinder which is inserted in the bore h .

5. A strip r (Fig. 8) of which the bent over part r^1 engages into the opening m and 75 serves to fix the second line-wire s ; the part r^2 of this strip lies in the grooves i and j and at r^3 is formed into a split cylinder 80 housed in the bore k .

6. Two hollow contact pins formed by a strip t hammered into the shape shown in Fig. 9, so as to serve as a receptacle for a 85 spring u (Fig. 10).

The whole device, mounted as explained, 90 is placed in the metal plug casing v and is retained therein by the push-pin m which passes through both walls of this casing, and projects on each side of the latter.

It is easily understood that the split cylinder r^3 inserted in the bore k is in permanent contact, by means of the strip r , with one of the poles of the line, while the contact between the part q^4 situated in the bore h and 95 the other pole only takes place when the metal ring n of the push-pin is between the strips o and q , the lighting and extinguishing of the lamp being thus obtained by the displacement of the push-pin in one or the 100 other direction.

It can be seen that the metal parts of the socket are easily manufactured without loss and with the minimum working possible.

On the other hand mounting is effected 105 without the assistance of any tool and the shape and arrangement of the members secure a satisfactory working.

What I claim as my invention and desire to secure by Letters Patent of the United States is:—

1. A socket for incandescent electric lamp holders comprising in combination a block of insulating material having a central cavity lateral and transverse channels and two cylindrical apertures in its base, contact pins inserted in said cylindrical apertures and held therein by friction, bent members formed of sheet metal and held in said lateral and transverse channels by friction, said members serving to fix the line wires and to establish contact between said wires and said contact pins, and a laterally movable switch pin coacting with said bent members to make and break contact.
2. A holder for incandescent electric lamps comprising a metal casing, a porcelain block inserted in said casing said block having a central cavity lateral and transverse channels and two cylindrical apertures in its base, contact pins inserted in said cylindrical apertures and held therein by friction, bent members formed of sheet metal and held in said lateral and transverse channels by friction, said members serving to fix the line wires and to establish contact between said wires and said contact pins, and a laterally movable switch pin coacting with said bent members to make and break contact.
3. A lamp holder for incandescent electric lamps comprising in combination a metal casing, a truncated cone-shaped member of insulating material within said casing said member having a transverse bore, a longitudinal groove extending from the top of the member to a central cavity thereof, a second longitudinal groove extending from

said cavity to the bottom of said member and connected by a transverse groove with a circular bore in the base of said member, a third longitudinal groove extending from the top of said member to the bottom thereof and communicating by a transverse groove with a second cylindrical bore in the base of said member and two transverse openings adjacent the top of said member, a laterally movable switch pin mounted in said transverse bore, a metal ring around said pin, a rectangularly bent strip of metal, one end of which is engaged in one of said transverse openings and serves to maintain one of the line wires in place therein and the other end lies in said cavity and partly surrounds the said switch pin, a second rectangularly bent strip of metal one arm of which partly surrounds the said switch pin and the other end of which engages in one of said circular bores in the base of said member, a third rectangularly bent strip of metal, one end of which is engaged in the other of said before mentioned transverse openings and serves to fix the second line wire in place said last mentioned strip being engaged in the other of said circular bores in the base of said member, a slideable hollow contact pin mounted in each of said circular bores in connection with said second and third strips respectively and springs in said contact pins, the said metal strips being held in position in said cone shaped member by friction.

In witness whereof I have signed this specification in the presence of two witnesses.

ALEXANDRE GOURJU.
